(57) **CLAIM**

The ornamental design for beverage serving tray with arm and hand supports, as shown and described.

DESCRIPTION

FIG. 1 is an upper right perspective view of the beverage serving tray with arm and hand supports.

FIG. 2 is a lower right perspective view of the tray of FIG. 1.

FIG. 3 is an upper left perspective view of the tray of FIG. 1.

FIG. 4 is a lower left perspective view of the tray of FIG. 1.

FIG. 5 is an upper front right perspective view of the tray of FIG. 1.

FIG. 6 is a lower front right perspective view of the tray of FIG. 1.

FIG. 7 is an upper rear left perspective view of the tray of FIG. 1.

FIG. 8 is a lower rear left perspective view of the tray of FIG. 1.

FIG. 9 is an upper rear left perspective view of the tray of FIG. 1.

FIG. 10 is a lower rear right perspective view of the tray of FIG. 1.

FIG. 11 is an upper front left perspective view of the tray of FIG. 1.

FIG. 12 is a lower front left perspective view of the tray of FIG. 1.

FIG. 13 is an upper front perspective view of the tray of FIG. 1.

FIG. 14 is a lower front perspective view of the tray of FIG. 1.

FIG. 15 is an upper rear perspective view of the tray of FIG. 1.

FIG. 16 is a lower rear perspective view of the tray of FIG. 1.

FIG. 17 is a front end view of the tray of FIG. 1.

FIG. 18 is a rear end view of the tray of FIG. 1.

FIG. 19 is a right side view of the tray of FIG. 1.

FIG. 20 is a left side view of the tray of FIG. 1.

FIG. 21 is a top side view of the tray of FIG. 1.

FIG. 22 is a bottom side view of the tray of FIG. 1.

(Continued)

FIG. 23 is another upper right perspective view of the beverage serving tray of FIG. 1 with a wine glass in a compartment.

FIG. 24 is another upper rear left perspective view of the tray of FIG. 1 with a beer mug in a compartment.

FIG. 25 is another upper rear left perspective view of the tray of FIG. 1 with plates stacked thereon.

FIG. 26 is another upper rear left perspective view of the tray of FIG. 1 with a wine bottle in a compartment.

FIG. 27 is another upper front right perspective view of the tray of FIG. 1 with a wine bottle in a compartment.

FIG. 28 is another lower rear right perspective view of the tray of FIG. 1 with a arm passing through an arm support and hand gripping a hand support; and,

FIG. 29 is another upper rear perspective view of the tray of FIG. 1 with a hand inserting a wine glass into the tray.

The broken lines in FIGS. 23-29 are for illustrative purposes and form no part of the claimed design.

1 Claim, 15 Drawing Sheets
